ROCK CRUSHER JAW

Kenneth V. Lutz, 10081 Carmen Road, Cupertino, Calif.
Filed Dec. 9, 1963, Ser. No. 329,097
6 Claims. (Cl. 241—217)

The present invention relates in general to rock crushers and more particularly to a rock crusher jaw.

Rocks being crushed by conventional crusher jaws have a tendency to slip during the crushing operation or to be ejected from the crusher jaw prior to being fractured. As a consequence thereof, the quantity of fractures of rock per stroke is lessened.

Furthermore, there is a tendency in rock crusher jaws to have uneven and excessive wear. A reason for this is that generally rocks do not begin to be fractured as soon as they enter the crusher jaws.

Accordingly, an object of the present invention is to provide rock crusher jaws that are more efficient, increase the quantity of fractures of rock per stroke and also provide a finer crushing action.

Another object of the present invention is to provide a rock crusher jaw that reduces the slippage of rock being crushed within the jaw, minimizes the ejection of rock from the crusher jaw prior to being fractured and also provides for a crushing action as soon as the rock enters the jaw.

Another object of the present invention is to provide rock crusher jaws that have improved crushing action and also have greater durability with more uniform wear.

Another object of the present invention is to provide rock crusher jaws that increase the quantity of rock fractured per stroke, improve the compaction quality of the crushed rock and produce finer crushing of rock.

Another object of the present invention is to provide an improved rock crusher jaw.

Another object of the present invention is to reduce work hazards by providing a crusher jaw that minimizes the projection of rocks therefrom.

Another object of the present invention is to reduce the operating costs of rock crushers by providing crusher jaws with improved production capacity, greater efficiency in crushing rocks and greater durability with more uniform wear.

Another object of the present invention is to provide a rock crusher jaw wherein rock is fractured as soon as it enters the jaw, thereby resulting in more uniform jaw wear and a finer crushing action.

Another object of the present invention is to provide a rock crusher jaw with increased crushing area to minimize the wear thereof.

Another object of the present invention is to provide rock crusher jaws with reduced surface flow of metal and distortion within the crusher apparatus.

Another object of the present invention is to provide a rock crusher jaw with improved gripping action and continued cleavage after the wearing of the teeth thereof.

Other and further objects and advantages of the present invention will be apparent to one skilled in the art from the following description taken in conjunction with the accompanying drawings, in which:

FIG. 1 is a perspective view of a rock crusher employing the crusher jaw of the present invention.

FIG. 2 is a diagrammatic vertical section taken along line 2—2 of FIG. 1.

FIG. 3 is an enlarged perspective view of the movable crusher plate for the crusher jaw of the present invention.

FIG. 4 is an enlarged perspective view of the stationary crusher plate for the crusher jaw of the present invention.

FIG. 5 is a fragmentary elevation view of the crusher jaw teeth of the present invention taken substantially along line 5—5 of FIG. 3.

2

Illustrated in FIGS. 1 and 2 is a conventional jaw crusher 10 of the type manufactured by the Iowa Manufacturing Company, which is suitable for employing the rock crusher jaw 11 of the present invention. Other jaw crushers, such as the well-known Blake type, Dodge type or combinations thereof, are equally applicable and suitable for employing the crushing jaw 11 of the present invention.

Briefly, the jaw crusher 10 comprises an eccentric shaft 12 (FIG. 2). Fixed to the shaft 12 are flywheels 13 and 14 (FIGS. 1 and 2). Adjacent one of the flywheels and secured to the shaft 12 is a pulley, not shown, which has a belt, not shown, trained therearound. The belt is driven by suitable drive means, not shown, to cause the pulley to rotate the eccentric drive shaft 12. A moving jaw wedge 15 (FIG. 2) is actuated by the eccentric shaft 12. Connected to the jaw wedge 15 is a toggle plate 16, which is also attached to a push wedge 17. Adjacent the push wedge 17 is a pull wedge 18.

Secured to the moving jaw wedge 15 is a movable jaw crusher plate 20 (FIG. 2). Adjacent and confronting the movable jaw crusher 20 is a stationary jaw crusher plate 21. The movable jaw crusher plate 20 and the stationary jaw crusher plate 21 comprise the crusher jaw 11 of the present invention.

Rock is fed into a feed hopper or inlet 23 (FIGS. 1 and 2) and passes between the movable jaw plate 20 and the stationary jaw plate 21. Horizontal and vertical action of the movable jaw plate 20 fractures the rock within the crusher jaw 11. The forward and downward movement of the movable jaw plate 20 forces the fractured rock to be discharged through an outlet 24 (FIG. 2).

The movable jaw plate 20 (FIGS. 2 and 3), which is made of suitable material, such as manganese steel, is in the form of a rectangular solid. As shown in FIG. 3, the movable jaw plate 20 comprises longitudinal side walls 25 and 26, transverse end walls 27 and 28, a rear surface 29 and a rock engaging surface 30. The plate 20 seats securely within the movable wedge 15 (FIG. 2) with the rear surface 29 resting against the wedge 15 and with the rock engaging surface 30 exposed. The transverse end walls 27 and 28 extend in the general direction of inclination of the movable wedge 15 (FIG. 2) and the longitudinal side walls 25 and 26 extend perpendicular to the general direction of inclination of the movable wedge 15 (FIG. 2).

According to the present invention, the rock-engaging surface of the movable crusher plate 20 comprises a plurality of transversely disposed ridges 31. The transverse direction is shown as the height and the longitudinal direction is shown as the width in FIG. 3. Successive ridges 31 are spaced an equal distance apart in the longitudinal direction of the plate 20. Each ridge 31 has a zig-zag configuration as it extends transversely of the plate 20. The angle at the zig-zag bend (FIG. 3) is preferably within the range of 10°—25°. It has been found that an angle in excess of 25° tends to retard the discharge of the rock and hold the same back to reduce the production output. An angle less than 10° is not as effective to reduce slippage and premature ejection of rocks. The cross-sectional areas of the ridges 31 are substantially trapezoidal. As shown in FIG. 3, the peaks 31a of the ridges 31 are coplanar and the bases 31b of the ridges 31 are coplanar. Confronting angular side walls 31c of successive ridges 31 form channels 32. Each channel 32 has a zig-zag configuration as it extends transversely of the plate 20. Successive channels 32 are spaced an equal distance apart in the longitudinal direction of the plate 20.

The channels 32 are relatively deep. The height of the channel 32 is greater than the width of the peak 31a of the ridge 31. As viewed in FIG. 5, the width of the peak 31a is X and the height of the channel 32 is Y. Y in the

present invention is greater than the dimension of X. It is also to be observed that the respective sides 31c of the channel 32 are in a plane or straight line until the bed of the channel 32 is reached. At the bed thereof, the channel 32 is arcuate.

The stationary jaw plate 21, which is made of suitable material, such as manganese steel, is in the form of a rectangular solid. As illustrated in FIGS. 2 and 4, the stationary jaw plate 21 comprises longitudinal side walls 40 and 41, transverse end walls 42 and 43, a rear surface 44, and a rock-engaging surface 45. The stationary plate 21 is fixedly secured to the housing of the jaw crusher 10 (FIG. 2) with the rear surface 44 contacting the housing and with the rock-engaging surface 45 exposed and confronting the rock-engaging surface 30 of the movable jaw plate 20.

As illustrated in FIG. 4, the rock-engaging surface 45 of the stationary jaw plate 21 comprises a plurality of transversely disposed ridges 46. The transverse direction is shown as the height and the longitudinal direction as the width in FIG. 4. Successive ridges 46 are spaced an equal distance apart in the longitudinal direction of the stationary plate 21. Each ridge 46 has a zig-zag configuration as it extends transversely of the plate 21. The angle at the zig-zag bend (FIG. 4) is preferably within the range of 10°-25°. It has been found that an angle in excess of 25° tends to retard the discharge of the rock and hold the same back to reduce the production output. An angle of less than 10° is not as effective to reduce slippage and premature ejection of rocks. The cross-sectional areas of the ridges 46 are substantially trapezoidal. The peaks 46a of the ridges 46 are coplanar and the bases 46b of the ridges 46 are coplanar. Confronting angular side walls 46c of successive ridges 46 form channels 47. Each channel 47 has a zig-zag configuration as it extends transversely of the plate 21. Successive channels 47 are spaced an equal distance apart in the longitudinal direction of the plate 21.

According to the present invention, the channels 47 are relatively deep. The height of the channel 47 is greater than the width of the peak 46a of the ridge 46. This is considered in the manner previously described in connection with FIG. 5. It is also to be observed that the respective sides 46c of the channel 47 are in a plane or straight line until the bed of the channel 47 is reached. At the bed thereof, the channel 47 is arcuate.

In operation, rock is fed into the hopper 23 (FIG. 2) which then passes between the rock-engaging surface 30 of the movable jaw plate 20 and the rock-engaging surface of the stationary jaw plate 21 of the crusher jaw 11. Rock is contacted by the zig-zag ridges 31 of the movable plate 20 and is engaged by the zig-zag ridges 46 of the stationary plate 21. Portions of rock may enter the zig-zag channels 32 of the movable plate 20 and the zig-zag channels 47 of the stationary plate 21. Thus, there is an improved gripping and retaining action between the crusher jaw 11 and the rock therein. Horizontal and vertical movement of the movable jaw plate 20 fractures rock within the crusher jaw 11. The forward and downward movement of the movable jaw plate 20 forces the fractured rock to be discharged through the outlet 24 (FIG. 2).

By providing zig-zag ridges and channels in the rock-engaging surfaces of the movable jaw plate 20 and the stationary jaw plate 21, the tendency of rock to slip during the crushing stroke is reduced. Likewise, the tendency of rock to be ejected from the crusher jaw 11 prior to being fractured is lessened. As a result thereof, the quantity of fractures of rock per stroke is increased and the production capacity is improved.

In addition, the zig-zag configuration for the channel and ridges tends to improve the durability of the rock crusher jaw. It has also been found that the zig-zag configuration for the ridges and channels of the rock crusher jaw provides a shearing action in addition to a crushing

action to improve the operation of the jaw in crushing hard rocks. Also, it has been found that a finer crushing action is produced with a more uniform and durable wear characteristics for the rock crusher jaw.

5 In the improved design for the configuration and construction of the channels 32 and 47, it has been found that the hard rock is being fractured as soon as it enters the jaws. This action results in more uniform jaw wear and finer crushing of the hard rock. The higher, straighter sides for the channels 32 and 47 tend to create an improved gripping action on the hard rock with continued cleavage action even after the jaws are worn. The deeper valleys for the channels tend to reduce surface flow of metal and lessen distortion of the jaws within the crusher apparatus.

It has also been observed that by having the zig-zag ridges and channel extend in the transverse direction as distinguished from the longitudinal direction that the ability to discharge crushed rock has improved. In this regard the zig-zag ridges are spaced in the longitudinal direction. Moreover, the flat wide peaks for the ridges greatly improve the wear and durability of the rock crusher jaws. This is accomplished by a flat rock-engaging surface and also extra ridge metal along the sides to compensate for conventional ridge wear. Coupling the forward and downward movements of the rock crusher jaw plates 20 relative to the stationary plate 21 with the zig-zag configurations of rock-engaging ridges thereof not only reduces slippage of the rock therebetween and the premature ejection of rocks, but, also, improves the rock crushing efficiency on the downward stroke. The movable plate 20 moves downwardly and obliquely across the stationary plate 21 to effect a better rock crushing action in conjunction with the zig-zag rock-engaging surfaces thereof.

While the present invention has been described in connection with a movable and stationary jaw crusher plate, it is apparent that the construction of the rock-engaging surfaces is equally applicable when both jaw crusher plates are movable and when the crusher mechanism is other than a jaw and crusher units have a configuration other than that of a plate.

It is to be understood that modifications and variations of the embodiment of the invention disclosed herein may be resorted to without departing from the spirit of the invention and the scope of the appended claims.

Having thus described my invention, what I claim as new and desire to protect by Letters Patent is:

1. A hard rock crusher jaw comprising a first jaw crusher plate having a rock-engaging surface, and a second jaw crusher plate having a rock-engaging surface confronting the rock-engaging surface of said first jaw crusher plate, said rock-engaging surface of said first jaw crusher plate being formed with a plurality of spaced zig-zag ridges having trapezoidal cross-sectional areas defining zig-zag channels therebetween for contacting rock disposed between said first and second jaw crusher plates, said zig-zag ridges being formed of a series of angular turns extending in the height direction of said first jaw crusher plate, said zig-zag channels being formed with a depth greater than the width of the respective rock-engaging surfaces of the ridges having the trapezoidal cross-sectional areas.

2. A hard rock crusher jaw comprising a first jaw crusher plate having a rock-engaging surface, said rock-engaging surface being formed with a plurality of wide edge zig-zag ridges defining zig-zag channels therebetween for contacting rock, said zig-zag channels of said first jaw crusher plate being formed with flat sides and with a depth greater than the width of the respective wide edges of the zig-zag ridges, said zig-zag ridges being formed of a series of angular turns extending in the height direction of said first jaw crusher plate, and a second jaw crusher plate having a rock-engaging surface confronting the rock-engaging surface of said first jaw crusher plate

and said wide edges thereof, said rock-engaging surface of said second jaw crusher plate being formed with a plurality of wide edge zig-zag ridges defining zig-zag channels therebetween for contacting rock disposed between said first and second crusher plates, said wide edges of said second jaw crusher plate being arranged to confront said rock-engaging surface of said first jaw crusher plate, said zig-zag ridges on said second jaw crusher plate being formed of a series of angular turns extending in the height direction of said second jaw crusher plate, said zig-zag channels of said second jaw crusher plate being formed with flat sides and with a depth greater than the width of the respective wide edges of the zig-zag ridges of said second jaw crusher plate.

3. In a hard rock jaw crusher, a first jaw crusher plate having a rock-engaging surface, a second jaw crusher plate having a rock-engaging surface confronting the rock-engaging surface of said first jaw crusher plate, said rock-engaging surface of said first jaw crusher plate being formed with a plurality of wide edge zig-zag ridges defining zig-zag channels therebetween for contacting rock disposed between said first and second jaw crusher plates, said wide edges of said first jaw crusher plate being arranged to confront the rock-engaging surface of said second jaw crusher plate, said zig-zag ridges being formed of a series of angular turns extending in the transverse direction across said first jaw crusher plate, said zig-zag channels of said first jaw crusher plate being formed with a depth greater than the width of the respective wide edges of the zig-zag ridges, and means for imparting relative movement between said first and second jaw crusher plates for fracturing hard rock therebetween.

4. A hard rock crusher jaw comprising a first jaw crusher plate having a rock-engaging surface with a longitudinal and transverse direction, and a second jaw crusher plate having a rock-engaging surface confronting the rock-engaging surface of said first jaw crusher plate with a longitudinal and transverse direction, said rock-engaging surface of said first jaw crusher plate being formed with a plurality of transversely disposed zig-zag ridges having trapezoidal cross-sectional areas for contacting rock disposed between said first and second jaw crusher plates, each of said trapezoidal cross-sectional areas being formed with a wide, blunt edge confronting the rock-engaging surface of said second jaw crusher plate, said zig-zag ridges being formed of a series of angular turns in the transverse direction across said first jaw crusher plate.

5. A hard rock crusher jaw comprising a first jaw crusher plate having a rock-engaging surface, and a second jaw crusher plate having a rock-engaging surface confronting the rock-engaging surface of said first jaw crusher plate, said rock-engaging surface of said first jaw crusher plate being formed with a plurality of spaced zig-zag ridges extending in the general direction of an end wall of said first jaw crusher plate for contacting rock disposed between said first and second jaw crusher plates, said zig-zag ridges being formed to project at an angle relative to said end wall within the range of 10° – 25° , said zig-zag ridges being formed of a series of angular turns extending in the general direction of the end wall of said first jaw crusher plate.
- 10 6. In a hard rock jaw crusher, a first jaw crusher plate having a rock-engaging surface, a second jaw crusher plate having a rock-engaging surface confronting the rock-engaging surface of said first jaw crusher plate, said rock-engaging surface of said first jaw crusher plate being formed with a plurality of wide edge zig-zag ridges extending in the general direction of the height of said first jaw crusher plate for contacting rock disposed between said first and second jaw crusher plates, said wide edges of said first jaw crusher plate being arranged to confront the rock-engaging surface of said second jaw crusher plate, said zig-zag ridges being formed with a series of angular turns extending in the height direction of said first jaw crusher plate, and means for imparting relative 15 forward and downward movement between said first and second jaw crusher plates for fracturing hard rock therebetween.
